UNITED STATES PATENT OFFICE.

ARTHUR MIDDLETON ROSE, OF YONKERS, NEW YORK, ASSIGNOR TO THE
LOWELL MANUFACTURING COMPANY, OF MASSACHUSETTS.

DESIGN FOR CARPET.

SPECIFICATION forming part of Design No. 26,963, dated April 20, 1897.

Application filed March 9, 1897. Serial No. 626,687. Term of patent 3½ years.

To all whom it may concern:

Be it known that I, ARTHUR MIDDLETON ROSE, a citizen of the United States, residing in Yonkers, county of Westchester, and State 5 of New York, have invented a new and original Design for Carpet and Border, of which the following is a specification.

This invention comprises two parts, namely, the design A for a carpet and the design B 10 for a border; and I do hereby declare that the drawing accompanying this specification conveys to any one a clear understanding of the same and is sufficient to enable such person to use my invention.

15 The body A is characterized by circular figures and interspersed curving stemwork and flower forms.

The border B is characterized by a row of large circular figures along its inner margin

and curving stemwork and flower forms with 20 plumes projecting toward the outer margin.

What I claim as new, and desire to secure by Design Letters Patent, is—

1. In the design for a carpet, the body A, substantially as shown. 25
2. In the design for a carpet, the border B, substantially as shown.
3. The design for a carpet consisting of the body A, and the border B, substantially as shown. 30

In testimony whereof I have signed my name to this specification in the presence of two subscribing witnesses.

ARTHUR MIDDLETON ROSE.
